UNITED STATES PATENT OFFICE.

WILLIAM L. MEYER, OF ST. LOUIS, MISSOURI.

DESIGN FOR A CLIP OR RACK FOR DISPLAYING COMBS.

SPECIFICATION forming part of Design No. 33,849, dated January 8, 1901.

Application filed November 30, 1900. Serial No. 38,272. Term of patent 14 years.

To all whom it may concern:

Be it known that I, WILLIAM L. MEYER, a citizen of the United States, residing at the city of St. Louis, in the State of Missouri, have 5 invented a certain new and original Design for Clips or Racks for Displaying Combs, of which the following is a full, clear, and exact description, such as will enable others skilled in the art to which it appertains to make and 10 use the same, reference being had to the accompanying drawing, forming part of this specification, in which the figure represents a perspective view of the clip made according to my new and original design.

15 This invention relates to a new and original design for clips or racks for displaying combs, the characteristic feature being a plurality of oppositely-curved prongs rising from a base-plate.

As shown in the drawing, the leading or 20 material feature of my design consists of a plurality of prongs A, rising from a base-plate B at an angle, said prongs being alternately curved or bent in opposite directions, as shown.

Having described my invention, what I claim as new, and desire to secure by Letters 25 Patent, is—

The design for a clip, substantially as herein shown and described.

In testimony whereof I hereunto affix my 30 signature, in the presence of two witnesses, this 28th day of November, 1900.

WILLIAM L. MEYER.

Witnesses:

WM. H. SCOTT,
RALPH KALISH.
